CLAIM

The ornamental design for an inflatable photo booth, as shown and described.

DESCRIPTION

FIG. 1 is a top, [rear] front and right side perspective view of an inflatable photo booth showing my new design;

FIG. 2 is a [right side] front elevational view thereof;

FIG. 3 is a left side elevational view thereof;

FIG. 4 is a [front] right side elevational view thereof; and,

[FIG. 5 is a rear elevational view thereof; and,]

FIG. [6] 5 is a top plan view thereof.

[The broken lines portions of a photo booth representing the contour of inner wall structures are shown for illustrative purposes only and form no part of the claimed design.]

1 Claim, 5 Drawing Sheets**Matter enclosed in heavy brackets [ ] appears in the original patent but forms no part of this reissue; matter printed in italics indicates the additions made by reissue.**(56)
